UNITED STATES PATENT OFFICE

ROYCE A. BEEKMAN, OF SCHENECTADY, NEW YORK, ASSIGNOR TO GENERAL ELECTRIC COMPANY, A CORPORATION OF NEW YORK

PRIME-MOVER-GENERATOR PLANT

Application filed February 25, 1928. Serial No. 257,055.

My invention relates to prime-mover-generator plants wherein a prime mover constructed and arranged for a given direction of rotation and subject to damage when rotated in the reversed direction is used to drive a generator which, due to its connection in a power system, is subject to a motoring action with reversed rotation upon failure of its prime mover to supply the necessary torque 10 to drive it as a generator.

An object of my invention is to provide means for preventing such reversal and the consequent damage attending it.

In ship propulsion systems, especially 15 where it has been found desirable to use Diesel engines, it is common practice to provide a plurality of generating units because the smaller engines may be more easily constructed, installed and repaired. Furthermore, 20 such arrangements provide more economical and dependable operation for, as is well understood, it requires much less power to drive a ship at low speeds than at high speeds and by using a plurality of units it is 25 possible to use a lesser number of units operating at high efficiency to propel the ship at the lower speeds, and under any conditions of operation it is possible to withdraw defective 30 units from the system for the purpose of repairing them without incapacitating the ship or unduly slowing up its schedule.

In the case of direct current systems it has 35 been found desirable to connect several generators in series with one another in order to eliminate or compensate for speed variations of the several prime movers. When, however, the generators are thus connected there is the possibility that any one of the generators may motor with reversed rotation whenever its prime mover for any reason fails to 40 supply the necessary torque to drive it as a generator. Certain types of prime movers may be constructed for rotation in either direction but are more cheaply constructed for 45 rotation in a given direction. Such is the case of the Diesel engine. In either case, however, the prime mover is subject to damage when rotated in a direction opposite to the direction in which it is normally arranged 50 to function.

According to my invention I provide means for energizing the several generators while their prime movers are rotating in the correct directions and for automatically deenergizing any generator before, preferably just before, its speed approaches zero due to the motoring action of its generator and thus remove the motoring torque of the generator sufficiently to relieve its corresponding prime mover or to permit it to recover and continue 55 to run driving its generator as a generator and supplying power to the system. In this manner I am able to prevent a reversal of the prime mover.

My invention will be better understood 60 from reference to the following description when considered in connection with the accompanying drawing and its scope will be pointed out in the appended claims.

Referring to the drawing, Fig. 1 shows a 65 simplified diagram of connections diagrammatically illustrating a system in which my invention has been applied, and Figs. 2 and 3 show details of a switch mechanism which 70 may be used in said system.

Fig. 1 shows a propeller motor 1 provided 75 with a separately excited field 2 and arranged to be supplied with current from generators 3 driven by suitable prime movers 4, such as Diesel engines. The generators 3 are connected in series with one another and with the propeller motor 1 by conductors 5, 6, 7 and 8. Switching means may be provided 80 in this circuit for shorting out any generator or for disconnecting the motor from the generator, but since such arrangements are already well known and form no part of the present invention the diagram has not been complicated by illustrating them. The several generators 3 are provided with separately excited fields 9 which are connected 85 through conductors 10 and 11 to buses 12 and 13 which, in turn, are connected to a potentiometer 14. This potentiometer 14 is connected across a suitable source of supply 90 15 by conductors 16 and 17 and is adapted to regulate simultaneously the amount and direction of the exciting current supplied to the several fields of the several generators. In the circuit of each generator field is an 95 100

adjusting rheostat 18 and a cutout shown as a relay 19. The operating coil of the relay 19 is connected across the source of supply 15 through conductor 20, contacts 21 and contact member 22 of a switch mechanism 23, and conductors 24 and 25. Contact member 22 is normally biased against an abutment 26 by a weight or a spring 27 but upon the correct rotation of the prime mover 4 is moved against the contacts 21 to complete the circuit of the relay 19 which then closes and completes the field circuit of the generator 3 driven by the prime mover 4. Motor field 2 is connected across the source of supply 15 by conductors 28 and 29 and its degree of excitation is controlled by means of a rheostat 30 inserted in series with it.

The switch mechanism 23 may be of any suitable construction so long as it will maintain its contacts closed when the prime mover with which it is connected rotates in one direction and breaks this connection when the prime mover slows down abnormally or its direction of rotation is reversed a few degrees. The construction may be such as diagrammatically illustrated in Figs. 2 and 3.

Referring to these figures, it will be noted that as there illustrated the switch mechanism comprises two disks 31 and 32 placed in close proximity to one another with their lower portions immersed in a heavy oil 33. One of the disks 31 is free to rotate about its center while the other disk 32 is free to rotate between contacts 21 and abutment 26 against which it is normally biased by the spring 27, previously referred to. The disk 31 which is free to rotate is mechanically connected directly or through the agency of gears to the shaft of the prime movers 4. Usually it will be found desirable to have the disk 31 rotate at a greater speed than the prime mover. When the prime mover is rotated in the correct direction at a proper speed this disk will also be rotating in a corresponding direction and will exert a dragging effect on the other disk 32, due to the viscosity of the oil 33, with the result that the contact member 22 mounted on disk 32 will be moved against the force of the spring 27 into engagement with contacts 21 which are shorted thereby. As previously noted above, this completes the circuit of relay 19 which closes and completes the circuit of the field 9 of the generator 3 driven by the prime mover 4.

The switch mechanism above briefly described is in accordance with the invention of George R. Townsend whose application Serial No. 75,147, filed Dec. 12, 1925, for rotary switch mechanism, now Patent 1,677,008, granted July 10, 1928, is assigned to the assignee of the present application.

The operation of the system described is as follows: The prime movers 4 are started and as long as they rotate in the correct directions the switch mechanisms 23 directly

connected to them will complete the circuits of relays 19 across the source of supply 15 through the following circuit: conductor 20, contacts 21, contact member 22 and conductors 24 and 25. The relays 19 will close completing the circuits of the field coils 9 of the generators 3. Thereafter the degree of excitation of the generators is simultaneously controlled through the potentiometer 14. Individual adjustments may be made in each field circuit by means of the rheostats 18. The direction of rotation of the propeller motor 1 may thus be controlled according to the well known Ward Leonard system by means of the potentiometer 14. Provision is also made for controlling the field of the motor 1 by means of the rheostat 30 so that under various conditions the motor 1 may be properly adjusted for obtaining the best results.

If for any reason one of the prime movers 4 should slow down abnormally or stall due to the failure of fuel supply or for some other reason or otherwise lose its propelling torque, its corresponding generator 3 will tend to motor and rotate the prime mover 4 in a direction opposite to that in which it has been rotating. However, as soon as this reversal is initiated, and by this I mean that the prime mover has slowed down abnormally or actually reversed a few degrees, the switch mechanism 23 operates to open the circuit of the relay 19 which upon opening deenergizes the field 9 of the generator 3 which is motoring. This deenergizes the generator and prevents it from motoring further, thus permitting the prime mover either to come to rest or under certain conditions even to recover and again supply power to the system.

It is apparent to those skilled in the art that the proposed arrangement may be modified to meet varying requirements without departing from my invention which has been shown and described in connection with a simplified arrangement for the purpose of clearly illustrating the invention and I, therefore, aim in the appended claims to cover all such changes and modifications as fall within the true spirit and scope of my invention.

What I claim as new and desire to secure by Letters Patent of the United States, is:

1. A prime-mover-generator plant including a generator subject to reverse rotation due to motoring action, a prime mover for said generator adapted for rotation in a given direction only, and means mechanically connected to said prime mover, responsive when the prime mover slows down abnormally and before its speed approaches zero, for deenergizing said generator when it tends to reverse the direction of rotation of said prime mover.

2. In a ship propulsion system, a pro-

5 peller motor, a plurality of series connected generators for supplying power to said propeller motor, a plurality of prime movers adapted for rotation in a given direction only for independently driving said generators, and means mechanically connected to each of said prime movers for deenergizing its corresponding generator just before its speed approaches zero due to the motoring 10 action of its generator upon a failure of its prime mover.

3. In a ship propulsion system, a propeller motor, a plurality of series connected generators for supplying power to said propeller motor, means for exciting each of said generators, a plurality of prime movers adapted for rotation in a given direction only for independently driving said generators, switching means associated with each 15 of said prime movers for controlling the excitation of the generator driven thereby, means for biasing each of said switching means to the position in which it deenergizes the generator with which it is associated, and means connecting each of said switching means to its associated prime mover for overcoming said biasing means during rotation of said prime mover until just before its speed approaches zero due to 20 the motoring action of its connected generator.

In witness whereof, I have hereunto set my hand this 24th day of February, 1928.

ROYCE A. BEEKMAN.
